METHOD OF FORGING

George Spatta, Buchanan, Mich., assignor to
 Clark Equipment Company, Buchanan, Mich.,
 a corporation of Michigan

Original application February 21, 1930, Serial No.
 430,206, now Patent No. 2,027,406, dated Janu-
 ary 14, 1936. Divided and this application May
 4, 1931, Serial No. 534,747

9 Claims. (Cl. 29—156)

This invention relates to a method of forging a heated tubular blank by a series of endwise upsetting operations which thicken the walls of the blank and stretch them to form a collar of 5 cylindrical shape and having internal and external diameters greater than the internal and external diameters respectively of the blank. The operations also form a planar flange of the free end of this collar and in a plane normal to the axis 10 of the blank. The operations thus performed may conveniently be used as a step in the process of forming an axle housing such as is set out in my co-pending application Serial No. 416,537, filed December 26, 1929, issued as Patent No. 1,926,353 15 on Sept. 12, 1933, although the method herein disclosed is not to be specifically limited to this purpose.

In my co-pending application, Serial No. 430,206, filed February 21, 1930, (Case 22), issued 20 as Patent No. 2,027,406 on January 14, 1936, of which application the instant case is a division, I disclose a machine capable of performing the forging method herein set forth. While the use 25 of a machine of the type disclosed in the parent application is preferable in the carrying out of the instant process, my improved method is not limited to such a machine and may, if desired, be performed by other mechanical arrangements.

My invention will be best understood by reference 30 to the accompanying drawing in which a preferred embodiment of it is diagrammatically shown, and in which:—

Figure 1 is an elevation view, partly in section, 35 of a blank and forming punch and die used in the first step of my process;

Figure 2 is a similar view showing the work at 40 the end of the second step of the process; and

Figure 3 is a similar view showing the completed work.

45 Referring now to the drawing in more detail, the blank that is to be fabricated comprises a thin wall tubular member 1 of proper length, diameter, and wall thickness, the end section of which is heated to forging temperature and placed in a suitable clamping member which holds it against longitudinal displacement with the heated end of the blank projecting into a stationary die member 3 of suitable design.

A punch carried on a suitable ram is aligned 50 with the die 3 and adapted to be brought into reg-

istration therewith. The punch has a shoulder 4 which engages the outermost end 5 of the heated blank, as the die advances axially of the heated blank, and collapses the metal of that end into the section of the blank that is disposed within 5 the stationary die member. In Figure 1, the end section 5 of the blank is shown by a dash dot lines and these lines indicate the shape and size of the blank at the beginning of the first step in the instant process.

After the punch 2 has completed its travel into the die 3, the metal in the end section 5 of the blank has been forced inward radially of the blank to form a thickened wall section indicated generally at 6 in Figure 1. The walls of the blank 10 have been broken away in this figure to better indicate the shape of this thickened wall section 6. It will be noted that the inside diameter of the thickened portion 6, which conforms to the outside diameter of the nose 1 of the punch, is 15 materially less than the inside diameter of the original blank 1, and that the outside diameter 20 of the section 6 is slightly greater than the outside diameter of the original blank. The larger diameter portion 8 is tapered into the outer surface of the blank wall 1 by a taper 9 located adjacent the innermost end of the thickened wall section 6.

Upon the completion of this operation, the blank is unclamped and moved to a second die 30 into which the thickened wall section 6 is projected. This die also has a cooperating punch adapted to register with it and is equipped with a shoulder 10 adapted to engage the extreme end 11 of the thickened wall section 6 of the blank. 35

In Figure 2 I have shown the blank at the completion of this second step in the present process. The die 12 is shaped so that when the punch 13 registers with it the thickened wall section 6 of the blank 1 is forced outward to 40 form a flange 14 on the end of the blank. The nose 14' of the punch is of a diameter slightly greater than the internal diameter of the section 6, so that simultaneously with the axial shortening of the tube by this operation, the walls of the section 6 are stretched outward radially at the axially outer end of the thickened portion 6 so that their inside diameter is increased. The die 12 also is shaped to increase the external diameter 45 of the blank to form a collar 15 located ad-

jacent the flange 14. The thickness of the end section of the blank at the point of the flange 14 is obviously further increased by the operation of the tools in this second step of my process.

5 It is to be noted that during the operation in the second set of dies, the metal of the inside of the thickened portion 8, and at the axially inward part thereof, that is, the metal at the point 8a, is forced axially rearward or inward longitudinally of the blank. This produces a thickened portion 8c on the inside of and immediately to the rear of the previously thickened portion 8. The thickness of the material of the blank adjacent the thickened flange 15 is greatly increased 15 in that the outer diameter has been increased by the formation of the collar portion 15 and the inner diameter has been decreased by the formation of the metal at the point 8c.

At the completion of this second step, the 20 work is again unclamped and brought into registration with another die and re-clamped in place in that die. As will be seen in Figure 3, this die is provided with a cooperating punch 16 which has a shoulder 17 which engages the free end 18 25 of the flange 14 of the blank and with a tapered nose which spreads the walls of this section 14 to increase their internal diameter. As the punch is brought into registration with the work, the metal in the flange 16 and in the sub collar 15 30 is forced outward radially into engagement with the die 18 to thereby form a cylindrical collar 20 whose external diameter is materially greater than the external diameter of the blank 1 and whose internal wall is tapered as at 21 to join 35 it with the thickened wall section 22 formed inwardly of the blank 1 by the nose of the punch. The punch also forms a flange 23 whose external diameter is materially larger than the external diameter of the collar 20 and whose parallel flat 40 faces 24 and 25 are disposed in planes normal to the axis of the blank 1. It is to be noted that the metal for forming the thickened wall section 22 is obtained by pushing the metal 8c back axially of the blank, that is, in a direction parallel 45 with the axis of the blank.

Upon the completion of this third step in the process, the blank is removed and its opposite end heated and that end then brought successively into engagement with the punches and dies herebefore described to form a similar collar and flange on that end:

50 As is well understood by those skilled in the art of forging, the maximum amount of metal flow that can be made in one step is definitely limited, and if this amount is exceeded, the work is buckled or broken and is therefore defective. By proper design of the dies and punches used in the process, I am able to move a maximum amount of metal by each step of the process 55 without damage to the work. Obviously this reduces the number of separate steps necessary to fabricate the work and furthermore permits completion of the several steps of the process with one heating of the work, that is, during the 60 interval during which it is cooling to a temperature too low for proper forging.

The method, while primarily intended as a 65 step in the process of forming an axle housing set out in the teachings of my above mentioned co-pending application Serial No. 416,537, is obviously not limited to this general process and may be used for the purpose of forming a flange upon the end of any tubular blank.

Having thus complied with the statutes and 70 shown and described the preferred embodiment

of my invention, what I consider new and desire to have protected by Letters Patent is pointed out in the appended claims.

What is claimed is:—

1. The method of forging the end of a metal 5 tube which comprises, thickening the end of the tube radially by forcing it inward axially, then forcing the thickened portion out radially and in axially at the axial outer portion of the thickened part and forcing the metal in axially at the axially innermost portion of the thickened part, to increase the thickness of the tube at a point spaced axially inward of the part first thickened, then flanging the axially outer portion of the thickened part of the tube and increasing both 10 the thickness and the diameter of the portion of the tube in back of the flange.

2. The method of forging the end of a metal tube which comprises, thickening the end of the tube radially by forcing the metal inward axially 20 and radially, then forcing the thickened portion out radially and in axially at the axial outer portion of the thickened part and forcing the metal in axially at the axially innermost portion of the thickened part, to increase the thickness of the 25 tube at a point spaced axially inward of the part first thickened, each of the forcing operations being along the entire periphery of the tube simultaneously, then forcing the end portion of the thickened part of the tube radially outward to 30 form a flange.

3. The method of forging the end of a metal tube which comprises, simultaneously forcing the metal along the entire periphery at the end of the tube outward radially to form a flange, and simultaneously forcing the metal on the outside of the tube axially rearwardly to thicken the tube rearwardly beyond the rear face of the flange. 35

4. The method of forging the end of a metal tube which comprises forcing the metal at the end 40 of the tube outward radially by a series of operations to form a flange having front and rear faces, each of the operations forcing the metal simultaneously along the entire periphery of the end of the tube, and during the series of operations gathering metal along the outside of the tube rearwardly of the rear flange face to thicken the tube portion at the rear of the flange. 45

5. The method of forging the end of a metal tube which comprises, thickening the end of the 50 tube by decreasing the internal radius of the tube, then forcing the metal at the end of the thickened part radially outward to form a flange with a thickened portion of the tube axially rearward of the flange, then flattening the flange axially to 55 increase its radius, and forcing the metal outward axially back of the flange to increase the internal radius of the tube back of the flange while maintaining the thickness in excess of the original tube thickness. 60

6. The method of upsetting and flanging the end of a tubular arm which comprises heating said end, subjecting said end while heated to a series of endwise upsetting operations comprising initially gathering metal to thicken said end, and subsequently flaring and flanging said thickened end to produce a thickened radial flange joined to said arm by an enlarged thickened bearing seat portion. 65

7. The method of upsetting and flanging the 70 end of a tubular arm which comprises heating said end, successively subjecting said heated end to three endwise upsetting operations to form a thickened end expanded into a bearing seat, and a thickened radial flange at the outer end of said 75.

seat, and controlling the area of the die surfaces contacted during each of the successive operations whereby minimum heat is lost during the first two upsetting operations to insure completion of said three operations in one heat.

5 8. The method of flanging the end of a tubular member which comprises heating said end, upsetting said end in a series of steps to gather metal for thickening and expanding said thickened end to form a thickened bearing seat, and flanging the 10 extremities of said bearing seat to form a radially thickened flange without reheating said end.

9. The method of flanging a tubular member which comprises subjecting said member to end-wise upsetting to increase the wall thickness adjacent one end thereof, expanding the thickened portion radially, and forcing the end of said thickened portion outwardly to form a thickened radially extending flange joined to said member by a thickened bearing seat portion.

GEORGE SPATTA. 10
